US0D1061004S

(12) United States Design Patent (10) Patent No.: US D1,061,004 S
(45) Date of Patent: * Feb. 11, 2025

(54) SOCK

(71) Applicant: NIKE, Inc., Beaverton, OR (US)

(72) Inventors: James Hunt, Portland, OR (US);
Kristine Morich, Portland, OR (US)

(73) Assignee: NIKE, Inc., Beaverton, OR (US)

() Term: 15 Years

(21) Appl. No.: 29/906,076

(22) Filed: Oct. 31, 2023

(51) LOC (15) Cl. 02-04

(52) U.S. Cl.

USPC D2/980

(57) CLAIM

The ornamental design for a sock as shown and described.

DESCRIPTION

FIG. 1 is a right side front perspective view of a sock showing our new design;

FIG. 2 is a right side view thereof;

FIG. 3 is a right side rear perspective view thereof;

FIG. 4 is a rear view thereof;

FIG. 5 is a left side rear perspective view thereof;

FIG. 6 is a left side view thereof;

FIG. 7 is a left side front perspective view thereof; and,

FIG. 8 is a front view thereof.

The broken lines depicting the remainder of the sock form no part of the claimed design.

1 Claim, 8 Drawing Sheets
